UNITED STATES PATENT OFFICE.

GEORGE H. HURST, JR., OF SUMTER, SOUTH CAROLINA.

BLOOD-DRAINER FOR EMBALMING.

1,266,477.

Specification of Letters Patent. Patented May 14, 1918.

Application filed September 11, 1917. Serial No. 190,835.

To all whom it may concern:

Be it known that I, GEORGE H. HURST, Jr., a citizen of the United States, and a resident of Sumter, in the county of Sumter and 5 State of South Carolina, have invented a new and Improved Blood-Drainer for Embalming, of which the following is a full, clear, and exact description.

This invention relates to the blood-draining process used in embalming dead bodies, and the invention has to deal particularly with a novel blood-draining device which has for its general object to enable the drawing off of blood from the veins or arteries 15 with more ease and satisfaction than can be accomplished with any other method in use today.

A more specific object of the invention is the provision of a novel form of bottle having one or more valved tubes connected with its mouth at the top, and which tubes are adapted to be inserted in the veins or arteries of a corpse, and in the bottom of the bottle is a drain pipe having a trap therein and 20 a valve, so that when the bottle, after being filled with water, is opened by means of the valve in the drain pipe, a suction is produced through the tubes or conduits at the top, and consequently, as the water flows out, 25 blood will be drawn into the bottle from the corpse without any danger of air entering the arteries or veins.

With such objects in view, and others which will appear as the description proceeds, the invention comprises various novel 30 features of construction and arrangement of parts which will be set forth with particularity in the following description and claims appended hereto.

40 In the accompanying drawing the figure is a central vertical section of the blood-draining device.

Referring to the drawing, 1 designates a glass or other bottle which is molded with a 45 basin-shaped bottom 2 that has a drain outlet 3 at which is formed a nipple 4, and at the top of the bottle is a mouth 5 adapted to receive a stopper 6 through which extends one or more suction tubes 7 each having a 50 cock or valve 8. To each tube may be attached a hose 9 that will have a nozzle which is inserted into a vein or artery. The bottle may be molded with a handle 10 at its top by which the bottle can be conveniently car-

ried. Attached to the nipple 4 is a piece of 55 tubing 11 which is suitably shaped to form a trap, and connected with this tubing is a cock 12 which has in turn connected with it a drain pipe 13 leading to a point of discharge. 60

In use, the bottle 1 is filled with water and the cocks or valves 8 and 12 are closed. The suction tubes 9 are inserted in the punctured veins or arteries of the corpse, and when the valves 8 and 12 are opened, water will 65 flow out of the bottle, and in flowing out a vacuum or suction will be produced whereby the blood will be drawn into the bottle through the suction conduits 7—9. This forms an easy and convenient method for 70 drawing off blood and avoids the danger of air entering the body.

From the foregoing description taken in connection with the accompanying drawing, the advantages of the construction and 75 method of operation will be readily understood by those skilled in the art to which the invention appertains, and while I have described the principle of operation, together with the device which I now consider 80 to be the best embodiment thereof, I desire to have it understood that the device shown is merely illustrative and that such changes may be made when desired as fall within the scope of the appended claims. 85

Having thus described my invention, I claim as new and desire to secure by Letters Patent:

1. A portable blood-draining device, comprising a receptacle for containing a liquid 90 and having openings at its top and bottom, a stopper closing the upper opening to hermetically seal the receptacle, a tube extending through the stopper and provided with a valve, and a conduit connected with the 95 bottom opening and having a valve for controlling the outflow of liquid from the receptacle, whereby a vacuum is produced in the top of the receptacle to draw any blood from the corpse. 100

2. A portable blood-draining device for embalmers, comprising a jug-like receptacle having a mouth and handle at its top and having a discharge opening at its bottom, a stopper in the said mouth, a tube extending 105 through the stopper and through which blood is adapted to be drawn into the receptacle, and a tube connected with the open-

ing in the bottom of the receptacle for drawing off liquid from the latter, whereby a suction is produced in the top of the receptacle.

5. A blood-draining device for embalmers, comprising a receptacle, a plurality of tubes communicating with the top of the recepta-

cle and each being adapted to be connected with a device inserted in the corpse, a valve for each tube, a drain conduit connected with the bottom of the receptacle and including a trap, and a valve in the drain conduit.

GEO. H. HURST, JR.
